UNITED STATES PATENT OFFICE

CARL KRUG, OF FRANKFORT-ON-THE-MAIN, GERMANY

BUILDING UP OF MACHINE TOOLS, SPECIALLY GRINDING MACHINES

Application filed October 29, 1928, Serial No. 315,902, and in Germany October 26, 1927.

The main building elements of machine tools, as foundations, frames, under frames, standards, uprights, arms, tables or the like, are preferably cast of iron. The quantity of material used for this purpose is quite out of proportion to what would be necessary on account of the stresses to which these elements are submitted or of the admissible alteration of shape. Foundry technical reasons and the consideration of the treatment make it generally necessary to increase to a multiple the quantity of material which would be absolutely necessary for fulfilling the technical purpose of the machine tool. The reason for the almost exclusive use of cast iron is the simplicity with which by the casting process even the most complicated forms can be obtained.

By the modern development of the welding technics the possibility of using building materials possessing higher resistance and which are not moulded by casting process has been thoroughly altered.

This invention has for its object to do away with the utilization of cast iron preferably in order to reduce the cost of manufacture of the machines and to improve the machines with the aid of the welding technics which have only quite recently developed to perfectness and economy. It has already been proposed to build certain parts of driving engines, like casings of dynamos or foundation frames for the same from ingot steel sheets, but it has never been proposed to intentionally transform the existing types of machine tools so that it becomes possible and remunerative to use building bodies of steel for the several elements. One has, of course, to count with the increased expenses for the welding but these expenses are more than compensated by savings in expenses for transport, simplified working, suppression of the expenses for models, cheaper machines and serious reduction of storing expenses and general expenses, not to mention the advantage of being no longer dependent on the foundries and the saving of time as no models have to be made. It is however impossible to substitute simply wrought iron and ingot steel for the cast iron and to merely alter the cross sections in the relation 1 by 2, 5, i. e. in the proportion of the modulus of elasticity of these materials. The use of wrought iron and steel and the utilization of the welding technics require new peculiar forms. Specially disappear the gradual transitions at alterations of cross section peculiar to the casting process and the local accumulations of material, and in general all expenditures in material which are not absolutely required by the absolutely necessary degree of resistance and limitation of alteration of shape. A principal difficulty is the mounting of guide faces for moving machine elements. This difficulty is overcome according to the invention in that the connection elements with guide faces in completely finished state are detachably, adjustably and readjustably connected, with interposition of an intermediate element distributing and transmitting pressure, to the hollow-or frame bodies made of wrought iron, ingot iron or ingot steel sheet plates or webs by means of weldings. This requires the solution of several secondary problems for the machine elements with plane guide faces. These problems are evidently other than for elements which possess rounded guide faces, like round bearings, bushes or the like. Building elements with simple fitted block-supporting-or carrying surfaces are also joined in completely finished state, the adjustability and re-adjustability being however generally omitted.

It might be apprehended that the natural vibrations of the frames and of their elements, which are specially dreaded in the building of grinding machines, could not be securely avoided when these frames and their elements are made of thin rolled sheet metal plates. Calculation shows however that in preserving the same rigidity the natural vibration coefficients remain the same. As with a very little consumption of material the natural vibration coefficients can be taken considerably higher by increasing the degree of compactness of the several building elements, for instance by insertion of intermediate transverse bars, the new

manner of building produces considerably greater rigidity and resistance against prejudicial vibrations than hitherto.

The advantages of the new building method are considerable: extraordinary savings in wages, in expenses for material and power, light machines and consequently low cost for transport and little loading of ceilings, greater rigidity and resistance against vibrations, little losses from friction and power in the moved building elements, possibility of carrying out more rapidly, and shorter terms for delivery, cheaper machine installations, less space required for the manufacturing, suppression of the inaccuracies and of the re-fashioning owing to warping at the ageing of the cast, suppression of expensive models, of the expenses for storing, and of the high insurance premiums due to the liability of the models to catch fire, less expensive maintenance, possibilities to rapidly alter the shape, greater security against breaking in transport, unsensitivity against rough treatment, greater accuracy in the long run, owing to the re-adjustability of the guide faces, simplest possibility of using the most favorable material pair: steel and cast iron for guide faces, possibility of building experimental machines and special machines in the shortest delay without loss of time and without manufacturing of expensive models which, if not satisfactory, are without value, possibility of using standard building elements like track plates, webs, angle pieces, sliding face elements or the like.

For grinding machines the new building manner is especially advisable for the reason that the warping of the cast pieces owing to ageing is very prejudicial to the high degrees of accuracy of the grinding machines at the construction of the same as well as in service. The possibility of readjusting the guide faces is of decisive importance for the preservation of the initial high degree of accuracy of the machines, and it is especially important for eventual breaking of the grinding tools that brittle materials like cast iron be avoided. Just in the grinding machines the disparity between the actual consumption of material and that which would be necessary to fulfill the technical purpose, is very conspicuous. One needs only compare the dimensions of the small grinding wheels with the disproportionate shape of the whole machine.

This is why a machine tool of the class of grinding machines has been selected as example of the application of the invention.

In the accompanying drawings a surface grinding machine of the form of construction which has become known by the main German Patent No. 399,144 is shown in the Figs. 1 to 10.

Fig. 1 is a front elevation showing the grinding machine.

Fig. 2 is a section through the machine.

Fig. 3 shows in elevation partly in section the underframe for the grinding wheel spindle head stock.

Fig. 4 shows in section the bed and the table.

Figs. 5, 6 and 7 illustrate how building elements with plane guide faces are mounted.

Figs. 8 and 9 illustrate the mounting of a building element with round guide surface, i. e. the bearing for the grinding wheel spindle shaft.

In Figs. 1 and 2, 1 designates the slide with the grinding wheel spindle 2, which carries the main driving disc 3, the driving disc 4 for the pump and the grinding tool 5.

The slide 1 for the grinding wheel spindle is shiftably arranged on the underframe 6 and the table 7 is shiftably arranged on the bed 8, the underframe and bed having on the walls facing each other projections 9 ending in parallel vertical planes and adapted to be connected with each other by screw connections. Between them a clamping and adjusting device 10 is arranged enabling the spacing of the free ends of the uprights. The table 7 is connected with a piston movable in a cylinder 11 fixed on the bed 8. In this cylinder end the conduits 12 and 13 for the pressure oil flowing in and out, the regulating of which is effected by the piston slide 14, to which the pressure oil is supplied by a pressure pump arranged in the machine. The grinding wheel spindle slide 1 and the corresponding underframe 6, the table 7 and the bed 8 are four main building elements of complicated shape, which hitherto have been made of cast iron.

According to the invention they are composed of correspondingly cut plates of wrought iron or ingot steel and connected with each other by welding, so that predominantly hollow bodies or cells are produced which are preferably limited by right angles. The hollow bodies are stayed in the interior by horizontal and vertical partitions, supporting angle irons, webs and the like, which are connected with the main body by welding. In the figures the outer plates 15 are united with the inner plates 16, which may be of different shapes and dimensions, to form hollow bodies or cells. It is also possible that an inner plate extends through the outer plates and becomes itself an outer plate 17.

The connection of the several plates is effected by butt welding, by overlapping or by attaching by means of several welding points, according to requirement and accessibility of the welding points. For connecting two plates a third element, for instance an angle iron 18, may be used, which is connected with the two plates by welding.

135

In the bed shown in Fig. 7 in cross section the arrangement of the sliding surfaces for the movement of the table is shown. To receive the horizontal or approximately horizontal loads serve the sliding or guide faces 19, and to receive the lateral pressures serve the guiding faces 20. The slide faces consist of prismatic rods, worked with great accuracy, which by the fixation screws 21 10 with the aid of intermediate plates 22 are connected to the main body. By means of pressure screws 23 the guides can be adjusted and re-adjusted. Figs. 5 and 6 illustrate in elevation and section details of the 15 point at which the guide rod is connected to the main body.

In building elements, which serve exclusively for a fitting, the re-adjusting device may be suppressed, so that the finished fitted 20 block is connected to the main body merely by fixation screws, eventually with the aid of intermediate elements. Under circumstances a readjusting device may be preferably provided. This will be the case if the 25 mutual position of two main building elements, for instance of the underframes 6 and of the bed 8, has to be corrected (Fig. 3).

In Figs. 8 and 9 is 2 the grinding wheel 30 spindle with its bearing, which consists of a roller bearing 27 and a double thrust bearing 28 mounted in the common casing 29. This casing 29 is sunk in the bearing head 30 of the machine, which consists of wrought 35 iron or steel sheet plates 16 cut accordingly and welded together, and it is fixed in the casing by means of screws 31 and pressure elements 32. The shafts of the screws 31 move with clearance in the corresponding 40 holes of the bearing head so that the casing together with the shaft can be adjusted parallel to the axis of the grinding wheel spindle by little amounts required for the adjusting and then secured in the adjusted 45 position. In the flange of the bearing casing a set of adjusting screws 33 is further arranged, by which the angle to the axis of the grinding wheel spindle and to the axis of the bearing head may be altered by little 50 amounts necessary for the adjusting.

I claim:—

1. As an article of manufacture a frame of grinding machines built up of a multiplicity of cells formed of rolled sheet metal 55 and welded together preferably by spot welding in combination with machine tool slide ways having fitted and guide faces joined to the frame in finished state in order to improve the possibility of working.

60 2. As an article of manufacture a frame of grinding machines built up of a multiplicity of cells formed of rolled sheet metal and welded together preferably by spot welding in combination with machine tool 65 slide ways having fitted and guide faces

joined adjustably and re-adjustably to the frame in finished state.

3. As an article of manufacture a frame of grinding machines built up of a multiplicity of cells the walls of which are erected of rolled thin sheet metal not exceeding 5 mms in thickness and preferably welded together by spot welding in order to obtain the highest possible rigidity with the minimum amount of material.

75 4. As an article of manufacture, a frame of grinding machines built up exclusively of thin sheet metal plates of equal thickness throughout, forming a multiplicity of cells welded together by spot-welding.

80 In testimony whereof I affix my signature.
CARL KRUG.
